UNITED STATES PATENT OFFICE.

FREDERICK STAPP, OF DENVER, COLORADO.

HEAT AND SMOKE GENERATOR.

No. 915,239.

Specification of Letters Patent. Patented March 16, 1909.

Application filed August 17, 1908. Serial No. 448,965.

To all whom it may concern:

Be it known that I, FREDERICK STAPP, a citizen of the United States, residing in the city and county of Denver and State of Colorado, have invented certain new and useful Improvements in Heat and Smoke Generators; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in heating devices my object being to provide relatively small fuel receptacles, adapted to be distributed in orchards and gardens or in such localities in horticultural districts having orchards, gardens or vegetation of any kind that is liable to be injured by frost.

20 My further object is to provide a device which shall be exceedingly simple in construction, economical in cost, reliable, durable and efficient in use.

25 It is very important that a construction of this class shall be supplied at small cost since a great many of them are required in order to produce the desired effect. In other words, these relatively small heaters are placed at such intervals as will serve to raise the temperature of the air in the entire district to be protected, to a sufficient degree to prevent injury by frost or an undue fall in the temperature.

30 My device is preferably formed of two pieces of sheet metal which in blank form have their upper and lower edges parallel, while their opposite side edges are inclined toward each other from the upper to the lower edges of the plates, these edges preferably being equally inclined and therefore forming equal angles with the top and bottom edges of the plate. These two metal sheets

35 or plates, are bent and connected to form a fuel inclosure open at both ends. In forming this inclosure or receptacle the two shorter sides of the plates are lowermost and when the adjacent edges of the sheets are connected, a receptacle is formed which is largest at the top and smallest at the bottom, being frusto-conical or approximately frusto-conical in shape. The peculiar feature of this construction, however, lies in the fact 40 that both the top and bottom edges are curved whereby when the device rests upon

a plane surface, as the ground, it touches the latter, if perfectly level, at two points only, from which points the edge is upwardly curved forming spaces on opposite sides of 60 the receptacle for the entrance of air for purposes of combustion. When in use a quantity of fuel, as coal, is placed within the receptacle or inclosure and ignited. The fuel resting upon the ground and engaging the inner sides of the device, retains the latter in a stable position, thus preventing accidental disturbance.

Having briefly outlined my improved construction, I will proceed to describe the same in detail, reference being made to the accompanying drawing in which is illustrated an embodiment thereof.

In this drawing, Figure 1 is a view illustrating a piece of sheet metal adapted to form 75 one of my improved receptacles. The line upon which the sheet is separated is indicated, also the turned edges to form the seams of the receptacle, are indicated by dotted lines. This view indicates that the members which constitute the receptacle, may be cut without waste of material. Fig. 2 shows the two sheet metal members bent into proper shape to form the receptacle, their edges being turned to form the seams. In this 80 view the edges of the two members are not joined. Fig. 3 is a side elevation of the complete receptacle. Fig. 4 is a similar view looking at right angles to Fig. 3, and shown on a larger scale. Fig. 5 is a section taken 85 through the device on the line 5—5 Fig. 4. Fig. 6 is a section taken at right angles to Fig. 5 showing a quantity of fuel in place within the receptacle.

The same reference characters indicate the same parts in all the views.

Let the numeral 5 designate each of two pieces of sheet metal whose upper and lower edges are parallel. These two plates or sheets when bent to form the device 6, are 100 shaped as indicated in Fig. 2, the opposite edges of either member being bent to interlock with the opposite edges of the companion member, as shown at 7 and 8. After the bending of these sheets in such a manner as 105 to form a frusto-conical device, their upper and lower edges are still parallel but are curved so that when the two members are connected to form the device 6, the top and bottom edges of each member are curved 110 downwardly from the opposite ends of the two edges, whereby the bottom of the device,

which is smallest in diameter, when placed upon a plane surface, touches the latter at two opposite edges only, leaving two spaces 9 on opposite sides of the points of contact, 5 the upper outline of each space being curved both vertically and transversely, leaving air spaces between the ground or other plane surface and the lower edge of the receptacle. It will be understood that the upper edge of 10 the receptacle is correspondingly shaped. Hence, upon the top of the receptacle, a downwardly curved plate 10 may be placed, forming a cover for closing the receptacle whenever it shall be necessary to do so. By 15 reason of the peculiar shape of the top of the receptacle, this plate will be retained in position against lateral displacement.

In forming the device, the two flat sheets 5 are first bent at their opposite edges to form 20 the interlocking hooks 7 and 8; the sheets are then correspondingly curved by passing them through suitable rolls. Their edges are then interlocked and pressed tightly whereby the two members are securely connected to form the fuel receptacle. It will 25 thus be observed that the device is constructed without the use of solder or other material that will be melted by the heat. When the device is completed and placed upon the 30 ground or other level surface, it is tangential thereto at two opposite points, leaving air spaces between the bottom walls of the device and the ground or other plane surface. The device is then ready for use and a quantity 35 of coal 12 or other suitable fuel, may be placed within the walls of the device and resting upon the ground or other plane surface. When this coal is ignited, combustion is maintained for the desired purpose 40 by the entrance of air at the bottom of the device. When in use these devices will be placed at suitable intervals within the field or orchard to maintain the temperature of the air above the freezing or frost point. It 45 will ordinarily be necessary to prepare these devices in advance of the time when they will be used, namely, during the night. It will, therefore, usually be advantageous to protect the fuel by use of the top plate or cover 50 10, which, however, when the fuel is burning, should not ordinarily be employed unless it is desired to retard combustion. If this should be necessary, the plate may be ad-

justed to partly uncover the top of the receptacle. When in full operation, however, for heat generating purposes, the cover will not be needed. If, however, it is desired to produce smoke, the device should be at least partly closed at the top. 55

Having thus described my invention what 60 I claim is:

1. A device of the class described, composed of a plurality of sheet metal members, each member having its top and bottom edges parallel, the upper edge being longer 65 than the lower edge, the two members being curved and having their sides connected, the arrangement being such that the two shorter sides of the members are at the one extremity of the device and the two longer sides at 70 the opposite extremity, substantially as described.

2. A device of the class described, comprising an open ended receptacle having its extremities of different diameters and so 75 shaped that when either end of the device is placed upon a flat surface, it shall be tangential thereto at two opposite points.

3. A device of the class described formed of two pieces of sheet metal having two opposite edges parallel and their opposite side edges inclined, the two plates being bent and having their side edges connected to form a receptacle whose greatest diameter is at the 80 top and smallest diameter is at the bottom, 85 for the purpose set forth.

4. A device of the class described having the general shape of the frustum of a cone, but whose opposite extremities are tangential to a flat surface at two opposite points, 90 substantially as described.

5. A device of the class described formed of two substantially twin plates of sheet metal, whose upper and lower edges are of equal length, the two plates being curved to 95 form a device approximately frusto-conical in shape, its opposite extremities being of unequal diameters, substantially as described.

In testimony whereof I affix my signature 100 in presence of two witnesses.

FREDERICK STAPP.
